UNITED STATES PATENT OFFICE

WALTER F. ROGERS, OF CICERO, ILLINOIS, ASSIGNOR TO CROWN STOVE WORKS, OF
CICERO, ILLINOIS, A CORPORATION OF ILLINOIS

DESIGN FOR A STOVE

Application filed September 15, 1931. Serial No. 41,114. Term of patent 7 years.

To all whom it may concern:

Be it known that I, WALTER F. ROGERS, a citizen of the United States, residing in Cicero, county of Cook, and State of Illinois, have invented a new, original, and ornamental Design for Stoves, of which the following is a specification, reference being had to the accompanying drawing, forming a part thereof.

The figure is a perspective view of a stove showing my new design.

I claim:

The ornamental design for a stove substantially as shown.

WALTER F. ROGERS.
